LOCK LEVER FOR TELESCOPING ELEMENTS

Filed July 10, 1930

UNITED STATES PATENT OFFICE

JOHN SCHADE, OF HOLYOKE, MASSACHUSETTS, ASSIGNOR TO NATIONAL BLANK BOOK COMPANY, OF HOLYOKE, MASSACHUSETTS, A CORPORATION OF MASSACHUSETTS

LOCK LEVER FOR TELESCOPING ELEMENTS

Application filed July 10, 1930. Serial No. 466,952.

This invention relates to locks for telescoping elements, but more particularly has reference to a lock lever which may be conveniently operated to positively bring the interlocking elements in locked and unlocked positions.

The actual interlocking members shown and described herein are not new, and this invention relates solely to the means employed for effecting the engagement and disengagement of such members.

This invention is utilized in connection with telescoping elements that constitute loose leaf binders, and in the accompanying drawings which form a part of this application,

Figure 1 is an elevation showing the telescopically arranged sections of a loose leaf binder equipped with the present invention, the parts being shown in locked condition.

Figure 2 is a section at the line 2—2 of Figure 1.

Figure 3 is a broken elevation similar to Figure 1 but showing the sections distended and in locked condition.

Figure 4 is a section at the line 4—4 of Figure 3.

Figures 5 and 6 are fragmentary side views showing the positions of the lock lever when the sections are respectively locked and unlocked.

Figure 7 is a section at the line 7—7 of Figure 3.

Figure 8 is a section similar to Figure 7 but showing the lock lever thrown back in the position that it assumes when the sections are unlocked.

Figure 9 is a detail elevation of the male locking member.

Figure 10 is a detail elevation of the lock lever, and

Figure 11 is a detail cross section through the male and female locking members, showing their relative positions when the sections are unlocked.

Similar numerals of reference denote like parts in the several figures of the drawings.

The sections of the binder are composed of back portions 1 and 2 which are in telescopic relation so as to slide one upon the

other, and side portions 3 and 4 which extend at right angles to the back portions 1, 2, and to these side portions are secured inwardly projecting posts 5 and 6 that penetrate, in the usual manner, suitable holes in the loose leaf sheets.

The lock proper comprises a female member 7 secured to one section, in the present instance, the section 1, and having a short indented threaded strip 8, these threads extending beyond the inner surface of the member 7, and a male member 9, adapted to enter the female member and to operate in the manner presently to be explained.

This male member 9 has a groove 10 extending throughout its length and threaded as shown at 11 adjacent one side of this groove, and the outer end of this member 9 is reduced in diameter as shown at 12, and a finger lever 13 has an opening 14 at the lower end conforming to the cross section of the cutaway portion 12, and in assembling the lock, this cut-away portion is inserted through the opening 14 and then passed through a circular opening (not shown) in the side 4 and through a washer 15 on the outer face of this side, and the end of the part 12 is then riveted over against said washer.

It will therefore be clear that the male member 9 may have a rotary movement, and that the finger lever 13 is secured to the member 9, so that any swinging movements of said lever will cause rotary movements of the member 9.

It will be further noted that the lever 13 is closely confined to the side 4 so that a lip 16 which is formed along the upper edge of the lever 13 will, when the lever is moved to locking position, abut the outer edge of the side 4, the latter being cut away for purposes of convenience, as shown at 17 and 17', the smaller slot 17' affording access to the lip 16.

When the lever 13 is elevated to disengage the members 7 and 9 the member 9 will be rotated so as to bring the groove 10 immediately beneath the projecting threads of the strip 8 and in this position the telescoping sections of the loose leaf binder will be free to be distended or contracted.

Furthermore, when this lever 13 is swung upwardly to effect the result just noted, it will abut the edge of the side 4, and thus prevent any overthrow of the member 9, so that 5 the free sliding movements of the members 7 and 9 will be assured, these relative positions of the locking members being clearly shown at Figures 8 and 11, particularly the last figure which is made on a large scale.

10 When the lever 13 is swung downwardly it will impart a quarter turn to the male member 9 which will bring the threaded portion 11 of said member into engagement with the threaded strip 8 of the female member, 15 and the sections of the binder will thus be locked, and when this locked position has been brought about, the lever 13 will have abutted the upper edge of the cut-away portion 17 of the side 4 so that there can be no 20 excessive rotation of the male member 9 such as would cause the threads to wedge together too tightly.

In unlocking the sections a finger is simply placed below the lip 16 and the lever 13 then 25 readily raised.

Locks of this sort have heretofore been constructed with a slot within the outer head of the male member, and the latter was then turned by any suitable device, such as a screw 30 driver or a coin, so as to bring about the desired relative positions of the locking members, but this always necessitated the presence of some device for insertion in the slot, and also overthrow of the male member in 35 either direction often occurred, and the present invention offers a very positive and efficient means for bringing about the desired relative positions of the locking members.

What is claimed is:—

40 1. A lock for telescoping elements, comprising an elongated tubular female member secured to the side of one of said elements and having a narrow threaded portion that projects beyond the inner face of said member; a male member swiveled to the side of the other telescoping element and having a groove throughout its length and threaded adjacent said groove, and a finger lever extending rigidly from the lower part of said 45 male member adjacent the last mentioned side and having a lip portion extending therefrom adapted to abut said side and adapted to be manually operated to interlock 50 and release the threads of said members.

55 2. A construction as in claim 1, the lever consisting of a sheet metal structure substantially contacting the adjacent side and having a lip along its outer edge, one end of the lip abutting the edge of said side when the 60 lever is operated either to lock or release the threads of said members.

3. A construction as in claim 1, the male and female members being free to move one within the other when the narrow threaded 65 part of the female member is within the

groove of the male member, the edge of the side adjacent said lip portion being adapted to abut said lip portion to arrest the swing of said finger lever whereby the overthrow of the male member is prevented and the locking and unlocking positions of said members are made positive.

4. The herein described improvement, comprising two elements having back portions slidable one upon the other and sides at right angles to said portions, loose leaf posts extending inwardly from said sides, an inwardly extending tubular female member secured to one of said sides and having a narrow threaded strip that projects beyond the inner wall of said member, a male member cooperating with said female member and swiveled to the other side and having a groove extending throughout the length of said male member the groove being of a width sufficient to loosely contain said strip, said male member being threaded adjacent said groove, and a sheet-metal finger lever rigidly secured to the base of the male member in substantial contact with the adjacent side and having a lip along its outer portion, the length of the lip being such that one end will abut the edge of said adjacent side when said lever is swung to either locking or unlocking positions, said edge being cut away so that said lever will be prevented from projecting beyond the edge when in locked position, and will afford ready means for raising the lip and lever to unlocking position.

In testimony whereof I affix my signature hereto.

JOHN SCHADE.
